Term of patent 14 years

(Cl. D4—4)

FIG. 2

FIG. 1

FIG. 3

FIG. 1 is a front perspective view of a bathroom unit showing our new design.

FIG. 2 is a fragmentary front view showing a portion of the right side of the lavatory cabinet and a portion of the area to the right thereof.

FIG. 3 is a fragmentary top plan view of the bathroom unit.

The rear and inside wall which adjoins the bathtub at the left thereof not shown are substantially plain. The side of the water closet not shown is substantially identical to that shown.

The dominant features of our design reside in the portions shown in full lines.

We claim:

The ornamental design for a bathroom unit, substantially as shown and described.
